UNITED STATES PATENT OFFICE.

WILLIAM E. MOORE, OF BEAVER, HERBERT FRANKLIN ALTER AND EDWARD AT LEE HANFF, OF PITTSBURGH, AND JOHN RAYMOND ECKLEY, OF NEW KENSINGTON, PENNSYLVANIA, AND FRANK WRIGHT, OF NEWPORT, KENTUCKY, ASSIGNEES TO PITTSBURGH ENGINEERING WORKS, OF PITTSBURGH, PENNSYLVANIA, A CORPORATION OF PENNSYLVANIA.

ELECTRIC FURNACE.

Application filed September 5, 1919. Serial No. 321,851.

To all whom it may concern:

Be it known that we, WILLIAM E. MOORE, a citizen of the United States, and a resident of Beaver, county of Beaver, State of Pennsylvania, HERBERT FRANKLIN ALTER and EDWARD AT LEE HANFF, citizens of the United States, and residents of Pittsburgh, county of Allegheny, and State of Pennsylvania, JOHN RAYMOND ECKLEY, a citizen of the United States, and a resident of New Kensington, county of Westmoreland, and State of Pennsylvania, and FRANK WRIGHT, a citizen of the United States, and a resident of Newport, county of Campbell, and State of Kentucky, have invented a new and useful Improvement in Electric Furnaces, of which the following is a full, clear, and exact description.

Our invention relates to electric furnaces of the tilting or rocking type, and it consists in the combinations, constructions and arrangements herein described and claimed. Heretofore, it has been customary to mount a furnace on rockers, extending longitudinally underneath the bottom of the furnace, which rockers run on horizontal tracks, also mounted underneath the furnace. There is frequent trouble with this arrangement, due to the accumulation of dust, dirt, slag and metal on the rocking surfaces and more particularly due to the fact that the furnace bottom occasionally "cuts through" and "gums up" the furnace rockers and tracks with molten steel. There is another difficulty due to the fact that the furnace rockers, when placed underneath the furnace, result in a very long forward travel of the spout when tapping, so that the crane-man, while the furnace is being tapped, must "rack" his crane, in order to keep the ladle underneath the furnace spout.

An object of the present invention is to overcome these difficulties. To this end we mount heavy steel cast rockers or trunnion frames on the sides of the furnace shell and so proportion the radius of the rocking circle on the same, as to make the stream pouring from the spout impinge at substantially the same place in the receiving ladle

when the furnace is tilted in tapping same, thus avoiding the necessity of "racking" the crane supporting the ladle. This arrangement also obviates the difficulties from dirt, dust and accumulation of slag and metal on the rocker tracks, thus resulting in easy 55 tilting and cleaner, safer work for the operatives.

The fact that the rolling circle or radius of the furnace rockers has been so much reduced and the rocking tracks are always 60 clean makes the furnace tilt so easily that even quite large furnaces are readily tilted by hand.

Heretofore, owing to the heavy work required by tilting, it has been customary to 65 place tilting means in the pits underneath the furnace. These sometimes consist of a crank shaft connected by two pitmen up to the back end of the furnace shell. At other times the tilting means consist of hydraulic 70 cylinders, placed in the same location and still other forms consist of vertical swivelling screws, actuated by swivelling gear driven nuts placed underneath the back side of the furnace. These all require great 75 depth of pits and foundations under the furnace, thereby increasing the cost and are all subject to rapid wear and tear, due to the accumulation of ash, slag, etc., as the motor and tilting gears are generally placed 80 underneath the working floor level. They are also, in this position, especially objectionable when the furnace bottom "cuts through" and pours its contents of molten metal in and around the motor, worm gears, 85 cranks, screws, valves, etc., thus "gumming them up" and requiring great labor, delay and cost for repairs.

A further object of our invention is to provide a simple device for tilting the furnace, free from all troubles, due to dust, dirt, slag, molten metal, etc., and all well above the floor, making inspection easy and repair convenient.

For operating the electrode arms when 95 adjusting the arcs as the carbon electrodes wear away, it has heretofore been customary to mount motor winches directly on the fur-

nace shell, engaging racks connected to the electrode arms, or in some cases the motors are geared to vertical screws, which engage the electrode arms. This results in a great deal of complication in and around the furnace shell, which is specially objectionable, on account of the heat, dust and dirt incident to the operation of the electric furnace, thus producing many burn-outs in the 10 motors and great wear and tear to the gears. Also due to the tilting action of the furnace, the motor when attached to and tilting with the furnace tends to spill the oil out of its bearings and injure its windings and run 15 its bearings hot.

To avoid these and other objectionable results we have provided novel means for operating the electrode arms, in which the winches are mounted in the sub-station wall, 20 where they are protected from the dust and dirt, but are made readily accessible. These means are fully described and claimed in divisional application No. 500,137, filed September 12, 1921.

25 A further object is to provide a plurality of furnaces, having their transformers, charging doors, tapping spouts, etc., so arranged as to permit the placing of the furnaces closely together in a row, thereby 30 effecting an economy in space and permitting the furnaces to be conveniently charged.

35 A further object is to provide novel means for operating the furnace doors consisting of levers and links which are so arranged as to cause the doors to move in a straight line, 40 means being provided for holding the doors in their open or their closed positions.

45 A further object is to provide an electrode gland made of cast iron which, if melted by the high heat of the furnace, will not injuriously contaminate the steel within the furnace. We also provide means for eliminating the magnetic effect to which cast iron is subject.

50 A further object is to provide a novel form of electrode clamp.

Other objects and advantages will appear in the following specification, and the novel features of the invention will be particularly 55 pointed out in the appended claims.

Our invention is illustrated in the accompanying drawings, forming part of this application, in which,

Figure 27 is a section along the line 27—27 110 of Figure 25.

In carrying out our invention, we provide a suitable base 1, upon which are mounted horizontal supports 2 and 3 for rockers or trunnion frames 4 and 5 respectively. The trunnions are mounted at the sides of the furnace body or crucible so as to permit the furnace to tilt forwardly and backwardly. The means for tilting the furnace consists of a hand wheel 6 at the end 120 of a screw shaft 7 which is journaled in a swivelled bearing 8 on the floor column 9. The screw shaft is provided with collars 10 for preventing endwise motion. Swivelled in an extension 11 of the trunnion frame 4 125 is a nut 12 which receives the threaded portion of the screw shaft 7. The tilting means, it will be noted, is well above the floor, making ready inspection and repair convenient, and being free from all troubles 130

due to dust, dirt, slag, molten metal, etc. The screw shaft 7 may be actuated by the motor 13, if desired.

5 Electrode arm-supporting columns 14 are carried by the trunnion frame 5 and the electrode arms 15 are movable along the columns to adjust the arcs. For this purpose, we mount motor winches 16 inside the 10 sub-station wall 17, where they are protected from heat, dust and dirt by the sub-station 18 and also by the removable screen or cover 19. The motor winches 16 are connected with the arms 15 by cables 20 which pass underneath the floor 21 around sheave 15 wheels 22, thence upwardly through the columns 14 to suitable sheaves 23, down around the sheaves 24 and are fastened to the sheave brackets 25. This greatly simplifies the furnace structure and reduces the troubles, delays and costs of the ordinary structure.

As it is sometimes desirable to hoist the electrode arms when no power is available for operating the electrode winches, we also 25 provide a hand crank gear 26, connected by sprockets 27 and chains 27 to the winches. This has a crank shaft placed at convenient height and the chain 27 is made adjustably taut by eccentric hand crank shaft bearing 30 28 clamped in housing 29, attached to lintel beams 30, built into the opening of the sub-station wall. The cranks 31, when swung backward, disengage the flattened head on the end of the sprocket shaft 27", so that 35 the shaft may then revolve freely when turned by the motor without revolving the crank.

It has heretofore been customary with furnaces of the tilting type, to mount the 40 pouring spout at 90° from the rocking axis of the furnace, and to mount the transformer back of and diametrically opposite the pouring spout. Owing to the travel of the furnace forward, when rocked, to tap, 45 and the radial height at which the electrode cables are connected, this means very long secondary or electrode cables, and a great deal of slack must be provided in the cables to allow the furnace to rock as required.

50 Where the position of the transformer is back of the furnace and opposite the spout, it has been heretofore customary to place the charging doors in the sides of the furnace, spaced 90° from the tapping spout. 55 This has made it necessary to pour the slag out through the tapping spout of the furnace and into the ladle pit, which results in excessive heat in the ladle pit and delay in handling the ladle, due to the quantity of 60 very hot slag which must be removed from the furnace only a short time before tapping.

The arrangement of the charging doors on the side precludes the possibility of feeding the furnaces efficiently, as in our im-

proved arrangement. According to our invention the several furnaces are arranged in a row, the tilting axes of the furnaces being parallel to the row, and the tapping spouts 32 at right angles to said row. With this arrangement, the furnaces may be spaced closely together, with the charging doors 33 opposite the spouts. A track may be carried along back of the row and parallel to the line of furnaces, so that the charging machines may be operated and the charging buggies or boxes used conveniently, as is usual with open hearth furnaces.

The arrangement of the charging door diametrically opposite to the tapping spout enables a slag pit 34 to be placed underneath the charging door, covered by suitable floor plates into which slag box 35 can be placed for conveniently receiving the slag when the furnace is rocked backward, without contaminating the ladle pit. This arrangement also permits of an underfloor slag-conveying track running parallel to the line of furnaces in which slag cars may be used, as is convenient in larger plants.

90 In furnaces at present on the market, it is customary to mount the electrode arms to travel on a column-like frame work, consisting of I beams or channels standing vertically to one side of the furnace, and a beam 95 or channel on each side of each of the electrode arms. There is then usually a mechanical electrode arm extending out over the center of the furnace, and the electrode clamp is mounted on the end of the arm and 100 electrically insulated at its point of attachment to the arm. There is then usually applied an overhead electrical electrode arm for conducting the electricity out to the clamp. This is a highly objectionable construction, in that the insulation is immediately over the openings in the roof, where it is subject to the smoke, flames and gases which leak out around the electrode glands; also due to the fact that the electrical currents must thus be carried between portions 110 of the frame work of magnetic material, closed or partly magnetically closed, producing high self induction and losses from the heavy alternating currents, and for the 115 further reason that the arms, being stationary, so far as horizontal arrangement is concerned, greatly interfere with handling the furnace roof, when it must be removed.

120 In our furnace the electrode arms are carried on turned pipe columns 14 by means of sleeve-like cross heads 36; guided by anti-friction rollers 37. These sleeves are held in their correct vertical plane by means of feathers 38, attached to the columns, which 125 are engaged by feather ways 39 in the cross heads 36. The feathers, however, are cut short at the top end, so that cross heads may over-run the feathers at their extreme upper limit of travel, and then may be swiv- 130

elled to the right or left to clear the furnace roof, or by means of additional feather-ways 40, see Fig. 4, when swung, may be lowered in their changed positions, so as to clear the 5 furnace roof and make the clamps and arms accessible from the floor position, at the same time clearing the way for sling chains to lift the roof, thus saving a great deal of delay or loss of time, when changing or ad- 10 justing the electrodes or when renewing roofs, as must from time to time be done while the furnace is in operation, with the minimum amount of lost time.

In order to minimize the self-induction 15 from the heavy alternating currents passing the electrode arm columns, we split the copper conductors 41, see Fig. 4, carrying one-half around each side of the column, so as substantially to neutralize the magnetic in- 20 duction. To avoid the difficulty due to insulation placed at the clamp over the electrode openings, we construct the electrode arms 15 of a box-like section, see Fig. 6, having channels 42 riveted at the top and bot- 25 tom between copper bars 43 forming the sides of the arm, the whole being insulated as shown, by suitable lapped plates 44, washers 45, and bushings and insulating material back at the point of connection with the col- 30 umn traveling cross head 36, where the insulation is not over the heat, flame and smoke, as when placed over the electrode clamp, and is in a position to endure a mini- 35 mum amount of break-downs and obstruc- tion.

There has heretofore been a great deal of difficulty with electrode clamps, which have usually been cast in one piece of solid metal with a split end having an opening, and 40 adjustable by means of a right and left hand screw. These clamps have in some cases been water cooled, but the bending action, due to the wide range of motion necessary for opening the clamp, soon causes the metal 45 to crack or break, because of the large amount of adjustment necessary on account of the very irregular electrodes, of commer- 50 cial grades.

To overcome this, we form a clamp of three parts,—a central portion 46, and wings 50 47 and 48 hinged to the central portion by heavy copper hinges 49. The wings are held together by means of a swing bolt 50 arranged to tighten by a wedge shaped key 55 51. The body of the renewable electrode clamp is cored for water cooling, and is made of copper or similar highly electrically conducting material. It is bifurcated as shown at 52 to allow some slight springing 60 motion when clamped to enable it to better fit the variably sized electrodes. It is also provided with fingers 53, protruding from the hinge leaves which are in mesh between similar fingers 54 of the wings. The wings

may be made of steel castings ribbed, and 65 by means of these leaved fingers, any heat developed in the wings is rapidly transferred by conduction to the fingers and then to the water chamber.

The electric furnace doors, being subject 70 to intense heat and requiring frequent opening and closing, are structures of great importance. Heretofore, it has been customary to hang the door on a lever, having formed on its door end a sector of sheave like or 75 grooved section which carries a chain supporting the door. As there are necessarily leaks around the door, at certain periods of the operation, the chain is embraced by flames gushing out from the furnace, which 80 soften the metal of the chain links and cause the links to pull tight, in such manner as to interfere with the free and easy working of the door.

To overcome these difficulties, we have 85 devised a straight line lever motion shown in Figs. 16 to 19. This comprises a door lever 57, mounted in a fulcrum stand 58, and engaging the links 59, which are attached to the door 60 by pins 61. The 90 attachment point of these links to the door is caused to move substantially in a straight line by suitably proportioned compensating links 62 which engage the upper ends of the links or levers 59, the links 62 being 95 suitably pivoted at 63 on the fulcrum stand 58. This door mechanism is counter-balanced by means of a weight 64, whose center of gravity 65 is placed above the center 100 line of the lever 57, a sufficient distance so that when the weight is up, the door is undercounter-balanced, in its closed position, and will remain closed, and when the weight is down the door is overcounter- 105 balanced and will remain open, thus avoiding the necessity for additional devices to hold the door open or closed.

The furnace doors are usually made of a metal, box-like casting which is open on its inner face and is lined with refractory 110 material, such as brick. Owing to the differential expansion between the door box and refractories, the brick are frequently loosened, so that when the furnace is tilted, they fall out of the door box into the furnace.

To avoid this, we have formed our door box 67, see Figs. 11, 12 and 13, of a curved or arch like form, so that when the refractory brick are set into the same, they arch 120 themselves in and thus are restrained from falling out when the furnace, with the door, is tilted through a wide angle.

Owing to the luminous flames which gush out around all openings in the furnace, 125 due to the plenum or gas pressure, when dirty or oily scrap is being melted, there is a great tendency to burn the bottom edges

68 of the door where the flames lap the lower edge and then follow up closely along the surface of the metal door box.

To overcome this difficulty, we provide a 5 rib or flange 69 which directs the flame forward and away from the outer face of the door box, so that it does not creep up tightly against the face of, and overheat, the door box. This rib 69 also serves to 10 cool the lower edge 68 of the box by conduction and radiation, and is still further cooled by other ribs 70 which join it. We have found that this construction greatly reduces the wear and tear on the door 15 casting. In order to make the door free to move in the vertical grooves 71 of cheek pieces 72, the ledges 73 on the vertical edges of the door box 67 are made to fit loosely therein.

20 The door sill 75 is arched downward, so that when lined with refractory brick it has a spout shape, guiding the stream of slag or steel to the center of the doorway. This door is still provided with wedge ribs 25 76 for holding the lower edge of the replaceable spout against the sill and with hooks 77 in which lugs on the spout rest for holding the spout in position. The adjustable cheek pieces 72 for the sides of 30 the door openings are heavy castings made with a specially heavy transverse section along the door opening, to rapidly extract the heat from the inner edges and carry it out to the exterior cooling ribs 78 which 35 tend to keep the heat of the cheek pieces within working limits. These cheek pieces 72 may be adjusted by loosening the bolts 78" which pass through the horizontally elongated openings 78", and moving the 40 cheek pieces into the desired position, and again tightening the bolts 78". Hooks 79 are cast on the cheek pieces for supporting a rod placed cross the door openings to support the hoe or hook when rabbling the 45 furnace.

The furnace shell is stoutly braced or reinforced around its top edge or opening, by means of heavy angle section circumferential steel castings, which are spliced together to form a ring-like stiffener 80. The two rockers or trunnions have their upper edges formed as a part of the stiffening circle and are supplemented by lintels 81, see Fig. 3, which at the door openings 50 are formed out over and away from the furnace shell, so as to allow the door to pass between the lintel and the periphery of the refractory lining of the shell, that is to say, the lintel carries the stiffening strength outside of the door, which permits the furnace shell over the door to be cut away, thus preventing any weakening or buckling which would result due to heating of the furnace shell at the point immediately over the doors, where the flames gush out.

In Figs. 20 to 23, we have shown the details of the column trunnion casting 5. This has a top stiffening flange 83 which joins and is spliced onto the two lintel sections of the top stiffening ring. The 70 lower edges or rocker sections of these castings are grooved as at 84 to roll upon the A frame or track. The upper portion of casting 5 is cored at 85 and ribbed to receive the electrode arm guide columns 14 75 arranged to be ribbed and welded into position. The top flange of this casting is drilled with holes 86 to be joined by riveted splice plates to the ends 81 of the lintels.

Trunnion 4, (see Figs. 24 to 27) is arranged on its rocker face to receive a toothed sector 4' which engages with a toothed rack 2' on the A frame (Fig. 2) to prevent sliding on its track, due to the reaction of the tilting screw swivelling nut 12, when 85 tilting. This rack sector is not necessary on the column trunnion as the reaction from the tilting screw appears only on the tilting screw side trunnion.

Heretofore, it has been customary to use 90 a water-cooled gland, surrounding the electrode at the opening where the same enters through the refractory roof. This is for the purpose of cooling the roof to prevent the wear of the refractories, cooling the 95 electrode, to prevent its oxidation and reducing the escape of flame and the entrance of oxidizing gases. It has been customary to make these glands of non-magnetic material, such as brass or bronze, for where 100 magnetic material, such as iron or steel, has been used, there has resulted a high self-induction, causing a loss of power, due to the magnetic circuit encircling the alternating current passing through the electrode. 105 The use of copper or similar metals is highly expensive, and is also objectionable, for it occasionally happens, due to the cessation of water flow, that the gland melts and runs into the steel in the furnace, forming 110 an injurious content in the steel, and spoiling the "heat."

To overcome these difficulties, we make glands 88 of cast iron, as shown in Figs. 8 to 10, which, if it melts, does not injuriously contaminate the steel. To avoid the magnetic effect of the cast iron, we cast the same with an open space or gap 89, which may be filled with non-magnetic material, as for instance clay or asbestos, or 120 may have cast therein such material as nickel or bronze. This gland is provided with a water passage 90 which is connected by pipe openings 91. It is provided with a large flange 92 to cover the annular opening 125 between the roof and the electrode, which must necessarily be larger than the electrode, to allow for some shifting of the electrode, due to irregularity. This flange, it has been found, frequently cracks, due to 130

the differential expansion, in case the cooling water goes off. To overcome this, this flange is heavily braced to the water chamber by braces 93 and is provided with inwardly extending slots 94 to allow for the differential expansion.

15 The buffer spring 96 (see Figures 1 and 5) is arranged to engage a pad or projection 97 attached to the roof frames 80, so that the top of the electrode arm is caught by the spring, and the clamp end of the arm prevented from coming into contact with the electrode gland, irrespective of the height of the roof or the extension of the same, due to heat.

20 On the cross head 36 at its inner top edge are attached two horns or fingers 98 which project above the cross head, and are arranged to straddle and engage the castor sheave 25, mounted on top of column 14, so that when the arm is still further raised until the feather-way 39 overlies the feather 38, and the arm is swung, the castor sheave 25 will be automatically swung with it.

25 In Figures 1 and 3 we have shown the means by which the electrode arms are raised or lowered. A drum 99 is provided for each cable 20, only one drum being shown. The cables 20, as stated before, 30 pass underneath the floor 21. We provide a tunnel 39^a for each cable. The cable is wrapped several times around the drum to obtain a friction "bite" and is passed over a pulley 100, see Figure 1, and supports a 35 counterbalance weight 101. When the electrode arm has reached its uppermost limit of safe travel, the weight 101 will rest on the floor so that the cable 20 will be slackened and will lose its "bite," thereby allowing the drum to revolve freely inside the 40 coils of the cable without straining or breaking the hoisting mechanism. In like manner, when the spring 96 engages the buttress 97, see Figure 1, the cable is slackened allowing the drum to revolve harmlessly.

50 In order to keep the furnace door held tightly against the door opening, in the closed position of the door, we provide door retaining lugs 73^a, see Figure 13, which are arranged to be engaged by retaining strips 68^a adjustably attached to the lintels 81 so as to be adjusted toward or away from the door. The lower ends of the strips 68^a are 55 rounded so as to engage the door lugs 78^a only in the closed position of the door. The lower end of each of the strips 68^a also forms a hook so that a bar laid between two strips 68^a may be used as a rabbling bar.

60 A division of this application was filed September 12th, 1921, Serial No. 500,137, in which the inventions relating to means for raising and lowering the furnace electrodes, and for stopping the upward travel of said electrodes at certain predetermined limits,

and the location, housing, and protection of the motors and winding drums, have been claimed.

We claim:

1. An electric furnace of the rocking type 70 comprising a shell having a tapping spout, rockers or trunnions attached to the shell at diametrically opposite points and at right angles to the tapping spout, said rockers being arranged with the rolling surface 75 above the floor line and so formed as to make the stream issuing from the tapping spout travel in paths which meet the receiving vessel at substantially the same point.

2. An electric furnace of the rocking type 80 comprising a shell or crucible, trunnions attached to the sides of the shell, one of said trunnions having a swivelling nut, a tilting screw placed above the tilting center of the furnace and arranged to engage the nut 85 and means for operating the tilting screw.

3. An electric furnace of the rocking type comprising a shell, rocking trunnions attached to the shell on opposite sides thereof, 90 one of said trunnions having projections or eyes and electrode arm supporting columns attached to said projections or eyes.

4. An electric furnace of the rocking type comprising a shell, tilting trunnions attached to the sides of the shell, one of said trunnions having a toothed sector, a tilting screw for operating said last named trunnion, and stationary tracks for said trunnions, one of said tracks having a rack arranged to be engaged by said toothed sector for resisting the reaction from the tilting screw.

5. In an electric furnace, the combination of a furnace shell of cylindrical formation, having diametrically opposite doors, tilting trunnions or rockers placed on the sides thereof at right angles to the doors and opposite to each other, one of said trunnions being formed to receive electrode arm guide columns and the other formed to receive an element of the tilting means.

6. In an electric furnace, a shell or crucible, a counter-balanced door carried thereby, said door being arched outwardly and having an outwardly extending flame protecting flange or lip disposed at the lower edge of the door.

7. In an electric furnace, a shell or crucible, a counter-balanced door carried thereby, said door being arched outwardly and having an outwardly extending flame protecting flange or lip disposed at the lower edge of the door and heat radiating ribs adjacent to said flange.

8. In an electric furnace, a vertically slideable counter-balanced door, lifting links for said door, and compensating levers to give the lower ends of the lifting links a substantially straight line motion independently of any other guide means.

9. In an electric furnace, a vertically slideable door, a lever for operating the door, a counter weight for the door the relative weights and positions of the door, lever and weight as a whole being so chosen that the center of gravity of the whole is substantially vertically above the fulcrum of the lever, thus producing an under-balanced condition when the door is closed and an over-balanced condition when the door is open.
10. In an electric furnace, a cylindrical column or support, an electrode arm mounted on said column to travel therealong, a feather carried by said column and arranged to enter a feather way in said electrode arm to keep the latter normally from rotating on the column, the electrode arm being arranged to clear the feather at the upper end 20 of the column, thereby permitting it to be swung laterally and lowered.
11. In an electric furnace, an electrode arm of tubular or box like section, an electrode clamp carried by said arm at one end, a guide column, a crosshead sleeve for slidably securing the electrode arm to the column, and means disposed near the sleeve and remote from the heat for insulating the clamp from the sleeve.
12. In an electric furnace, an electrode arm, an electrode clamp carried by the arm at one end, an electrode arm guide column, a conductor carried by said electrode arm, said conductor being split and carried 35 around the column on opposite sides of the same, whereby self induction is diminished.
13. In an electric furnace, an electrode arm, an electrode clamp carried by the arm at one end, an electrode arm guide column, a conductor carried by said electrode arm, said conductor being split and carried around the column on opposite sides of the same, whereby self induction is diminished, and means for attaching electrical conductors to 45 the split end of said conductor.
14. In an electric furnace of the rocking type, the combination of diametrically opposite tapping and charging doors located at 90° to the rocking axis of the furnace, 50 said furnace being adapted to tilt backward for slagging and forward for tapping and a transformer placed to one side of and at about 90° to the line of doors.
15. In an electric furnace of the arcing electrode type, a renewable electrode holder, comprising a bifurcated body, having water circulating chambers in said body, with hinged joint sections and adjustable clamp wings.
16. In an electric furnace of the arcing electrode type, an electrode clamp comprising a water cooled body having a series of projecting fingers on each side thereof, and a pair of clamping wings having fingers arranged to enter between the fingers of the
- body and pins for hinging the fingers of the wings to those of the body.
17. In an electric furnace, a vertically slideable door, adjustable cheek pieces for guiding said door, loosely fitting guide flanges on the door arranged to engage said cheek pieces, and stop pieces carried by said cheek pieces, and arranged to be engaged by a portion of the door for forcing the latter against its seat in the closed position of the door.
18. In an electric furnace of the tilting type, the combination of a cylindrical shell with curved bottom, and having door openings, stiffeners around the top of the shell, 80 said stiffeners being bent or bowed away from the furnace shell over the door openings, and the shell being cut away over the door openings.
19. In an electric furnace, the combination of a guide column, a vertically slideable electrode arm of tubular or box-like structure having conductive sides, and a renewable electrode clamp set into the outer end of said arm, the conductive sides of said arm 90 being divided and carried around the column to the back side, the sides of said arm projecting backwardly around the column and behind same to form points of attachment for electrical conductors.
20. In an electric furnace, a vertically slideable cross head of sleeve-like construction, an electrode arm insulated from and supported by said cross head, a guide column for said cross head, and rollers carried by said cross head and arranged to bear on said guide column.
21. In an electric furnace, a vertically slideable cross head of sleeve-like construction, an electrode arm insulated from and 105 supported by said cross head, a guide column for said cross head, rollers carried by said cross head and arranged to bear on said guide column, and means for normally preventing the lateral rotation of said cross head with respect to said guide column.
22. In an electric furnace, a water cooled electrode clamp comprising a central portion, wings hinged to said central portion, and means for adjustably clamping the 115 wings to the electrode, said means comprising a swing bolt carried by one of said wings and a wedge carried by the other wing and arranged to be engaged by said swing bolt.
23. In an electric furnace of the rocking type, the combination of an open top shell, lined with refractory material, said shell having vertically slideable doors, a stiffener around the top edge of the shell and attached thereto, the stiffener being bowed or bent out and away from the furnace shell periphery, thereby allowing the doors to slide between the stiffener and the refractory lining of the shell.

24. The combination with an electric furnace having a roof provided with an opening therein, of a water cooled electrode gland comprising a split metal ring having an outwardly extending flange disposed near the bottom of said ring. 20
25. The combination with an electric furnace having a roof provided with an opening therein, of a water cooled electrode gland comprising a split metal ring having an outwardly extending flange disposed near the bottom of said ring, said flange being provided with radial slots. 25
26. In an electric furnace of the tilting type, a support, an electrode bearing arm slideable on said support, and a spring buffer carried by the arm and arranged to engage over said sheaves, said cables being secured to said electrode-bearing arm. 25

a portion of the furnace for cushioning the arm at the limit of its movement in one direction.

27. In an electric furnace of the tilting type, a support, an electrode-bearing arm slideable on said support, a rotatable sheave bracket carried by said support, sheaves carried by the bracket, and cables for raising and lowering said arm arranged to pass over said sheaves, said cables being secured to said electrode-bearing arm.

WILLIAM E. MOORE.
HERBERT FRANKLIN ALTER.
EDWARD AT LEE HANFF.
JOHN RAYMOND ECKLEY.
FRANK WRIGHT.

DISCLAIMER

1,444,980.—*William E. Moore, Beaver; Herbert Franklin Alter and Edward At Lee Hanff, Pittsburgh; and John Raymond Eckley, New Kensington, Pa.; and Frank Wright, Newport, Ky.* ELECTRIC FURNACE. Patent dated February 13, 1923. Disclaimer filed January 14, 1939, by the assignee, *Pittsburgh Research Corporation*.

Hereby enters this disclaimer to claims 11, 12, 13, 14, 17, 18, 19, 20, 21, 23, and 27 of said patent.

[*Official Gazette, February 7, 1939.*]
